Primary Examiner — Jonathan J Han*Assistant Examiner* — Molly K. Orzechowski(74) *Attorney, Agent, or Firm* — ALSTON & BIRD LLP(57) **CLAIM**

The ornamental design for an outsole as shown and described.

DESCRIPTION

FIG. 1 is a perspective view of an outsole showing the new design;

FIG. 2 is a front view thereof;

FIG. 3 is a side thereof;

FIG. 4 is a cross-section perspective view of FIG. 5, taken along line 5-5 of FIG. 3;

FIG. 5 is a cross-section front view thereof, taken along line 5-5 of FIG. 3;

FIG. 6 is a cross-section perspective view of FIG. 7, taken along line 7-7 of FIG. 3; and,

FIG. 7 is a cross-section front view thereof, taken along line 7-7 of FIG. 3.

The broken lines illustrate portions of the outsole that form no part of the claimed design.

1 Claim, 7 Drawing Sheets(56)
